UNITED STATES PATENT OFFICE

123,424

DESIGN FOR AN ARM REST FOR CARDIO-METRIC MACHINE

Bradlee W. Williams and Homer S. Williams,
Chicago, Ill.

Application September 9, 1940, Serial No. 94,910

Term of patent 7 years

To all whom it may concern.

Be it known that we, Bradlee W. Williams and Homer S. Williams, both citizens of the United States and residents of Chicago, State of Illinois, have invented a new, original, and ornamental Design for an Arm Rest for Cardiometric Machine, of which the following is a specification, reference being had to the accompanying drawing, forming part thereof, and in which,

Fig. 1 is a top plan view of an arm rest showing our new design;

Fig. 2 is a front side elevation of the same;
Fig. 3 is a rear end elevation of the same;
Fig. 4 is a front end elevation of the same;
Fig. 5 is a rear side elevation of the same.

We claim:

The ornamental design for an arm rest for cardiometric machine, as shown.

BRADLEE W. WILLIAMS.
HOMER S. WILLIAMS.
